US00D992577S

(12) **United States Design Patent** (10) Patent No.: **US D992,577 S**
Chen et al. (45) Date of Patent: **** Jul. 18, 2023**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Kevin Will Chen**, Cupertino, CA (US);
Alan C. Dye, San Francisco, CA (US);
Aurelio Guzmán, San Jose, CA (US);
Christopher I. Wilson, San Francisco, CA (US)

(73) Assignee: **Apple Inc.**, Cupertino, CA (US)

(**) Term: **15 Years**

(21) Appl. No.: **29/844,113**

(22) Filed: **Jun. 27, 2022**

Related U.S. Application Data

(63) Continuation of application No. 29/750,502, filed on Sep. 14, 2020, now Pat. No. Des. 956,068.

(51) **LOC (14) Cl.** **14-04**

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outer broken lines in the FIGURE show a display screen or portion thereof, and form no part of the claimed design. The other broken lines in the FIGURE show portions of the graphical user interface that form no part of the claimed design.

1 Claim, 1 Drawing Sheet
